[57] CLAIM

The ornamental design for a sandal, as shown and described.

DESCRIPTION

FIG. 1 is a top front right perspective view of a sandal showing my new design;

FIG. 2 is a bottom plan view;

FIG. 3 is a top plan view;

FIG. 4 is a front elevational view;

FIG. 5 is a rear elevational view; and

FIG. 6 is a cross-sectional view.

The continuous textures on the top and bottom are shown partially in FIGS. 2 and 3 for convenience of illustration.

FIG. 1

FIG. 2
